UNITED STATES PATENT OFFICE.

GEORGE E. KING, OF NEWTON, MASSACHUSETTS, ASSIGNEE TO THE GAMEWELL FIRE ALARM TELEGRAPH COMPANY, OF NEWTON UPPER FALLS, MASSACHUSETTS, A CORPORATION OF NEW YORK.

AUTOMATIC WINDING MECHANISM.

1,258,909.

Specification of Letters Patent. Patented Mar. 12, 1918.

Application filed May 28, 1917. Serial No. 171,599.

To all whom it may concern:

Be it known that I, GEORGE E. KING, a citizen of the United States, residing at Newton, in the county of Middlesex and State of Massachusetts, have invented an Improvement in Automatic Winding Mechanisms, of which the following is a specification.

This invention relates to automatic winding devices, it being particularly applicable to weight-driven mechanisms, whereby the weight, when lowered to a predetermined position, will be automatically lifted and restored to initial position. Such a winding-device is of great value in connection with automatic repeaters which are employed in fire alarm telegraph systems, for the reason that it is of the utmost importance that they shall be kept wound and in service ready for immediate response at all times. It is understood, however, that the winding-device may be associated with other apparatus.

It is particularly applicable for use in connection with means for winding up the weight at any time without possibility of interfering with the simultaneous operation of the mechanism to be driven thereby. Such mechanism may comprise a weight and an endless chain connecting said weight with the driving-shaft of the mechanism to be actuated, and winding-means connected with said chain for lifting the weight, said parts being so arranged that a portion of the chain is movable in one direction by the falling weight to rotate the driving-shaft, while another portion of the chain with which the winding-means is connected may remain stationary, and a portion of the chain with which the winding-means is connected is moved by said winding-means to lift the weight while the portion of the chain connected with the driving-shaft may be in motion or remain stationary, and an electric motor is provided for driving the winding-means.

This invention has for an object the provision of a novel means consisting of an automatic device governed by parts operated simultaneously with the weight to cause the starting of the winding-mechanism when the weight falls, and to cause

the winding-mechanism to cease operating when said weight has been properly raised.

Another object of the invention is the provision of a circuit-controller for the circuit of the electric-motor, and means for controlling said circuit-controller upon both the rising and falling movements of the weight, thereby to close said circuit-controller when the weight falls to a predetermined position and to open the same when the weight rises to a predetermined position.

Another object of the invention is the provision of a novel circuit-controller for an alarm circuit adapted to be controlled by means operated upon both the rising and falling movements of the weight, but arranged to close the circuit to cause the alarm only when the weight falls beyond the position where it should cause the operation of the electric-motor, so that in case the electric motor fails to respond, an alarm will be sounded as long as the weight remains in such extreme position.

Another object of the invention is the provision of a single actuating-member for both circuit-controllers, and means arranged for movement by the rising and falling of the weight to operate said actuating-member.

Another object is in the provision of a normally closed switch in the motor circuit in series with the motor controlling switch that is adapted to be positively opened by engagement with a moving part of the winding-device during the operation of winding, and upon failure of the motor-controlling switch, to open the circuit, to protect the winding mechanism and motor from possible consequent damage.

Another object is the provision of a motor-controlling switch that is so arranged as to open quickly and to close quickly to prevent destructive arcing at the contacts thereof and to prevent injury to the motor or motor circuit; that has a simple, positive, and convenient adjusting means for determining the operation of the switch relative to the motion or position of the weight; that admits of a construction not liable to change after adjustment or to weaken any structure to which it may be attached; and

that admits of suitable connection with a conduit for the protection of the circuit wires.

Another object of this invention is the provision of a safety switch in the circuit to the motor, which is automatically opened by direct engagement of the weight, if wound manually or otherwise beyond the position where the automatic switch first referred to should have opened said circuit.

Figure 1 is a side elevation of an automatic winding-mechanism embodying this invention.

Fig. 2 is a horizontal section of the same, taken on the line 2—2.

Fig. 3 is a plan view of the circuit-controllers which are controlled by the operation of the weight.

Fig. 4 is an enlarged detail view of one of the circuit-controllers and operating-means therefor.

Fig. 5 is a sectional view taken on the dotted line 5—5, Fig. 3.

Fig. 6 is a detail of the traveling-member for the circuit-controllers.

Figs. 7 and 8 are details of one of the circuit-controllers.

Referring to the drawings, 10 represents a table arranged to support a telegraph repeater or other mechanism to be actuated, and which also serves as a support for the operating parts of the winding-mechanism; 30 represents the driving-shaft of the mechanism to be actuated, and 51 a sprocket-wheel mounted thereon and fast thereto. An endless sprocket-chain 52 passes over said sprocket-wheel 51, which is arranged with the two depending loop-portions 14 and 14^a. A weight 17 is suspended from the loop-portion 14, it having a swiveled yoke 16 connected with it which supports a pulley 15, around which the chain passes. A pulley 24 is received in and supported by the loop-portion 14^a, which is borne by a swiveled yoke 25, connected, by a turn-buckle, for adjustment, and an eye and link, with one end of a flexible connection 62, which is made as a sprocket-chain. Said chain 62, passes over a sprocket-wheel 60, borne by the shaft 46, and also over an idle pulley 60^a, and its other end is connected by a link with the lower end-portion of the weight 17.

That portion of the chain 52 which forms the outer side of the loop 14, is arranged vertically, tangentially with respect to the pulley 15, and the sprocket-wheel 51. That portion of the chain 52 between the two loop-portions 14 and 14^a passes under a sprocket-wheel 19 and over a sprocket-wheel 18 and idle pulley 22, said wheel 18 and pulley 22 being arranged, respectively, at opposite sides of sprocket-wheel 19, and the adjacent sides of said loop-portions are vertically arranged and disposed tangential 60 with respect to the peripheries of said

sprocket 18 and pulley 22. That portion of the chain 52 between the loop-portion 14^a and the sprocket-wheel 51 passes over idle pulley 26 and under pulley 27; and the pulley 26 holds the chain with the outer side 70 of the loop 14^a in vertical position and in tangential relation with the peripheries of the pulleys 24 and 26, and the pulley 27 holds the chain deflected and in tangential relation with the peripheries of the pulleys 26, 27, and sprocket 51.

The sprocket-wheel 19 is connected through a ratchet wheel and pawl with and forms a component part of the automatic winding-means to be described. The 80 sprocket-wheel 18 is provided with a ratchet wheel which is engaged and held by a pawl fastened to the frame, and when so held the intermediate portion of the chain 52, being that portion between the loop-portions 14 85 and 14^a, is held by it. This permits movement of those portions of the chain, including the outer sides of both loop-portions, independently of the intermediate portion.

Such independent motion of the outer portion of the chain 52 occurs when the sprocket-wheel 51 is permitted to rotate, and the weight to fall. As the weight falls, and the outer portion of the chain moves, the loop 14 is lengthened and the loop 14^a is correspondingly shortened.

The weight is adapted to be lifted by rotation of the sprocket-wheel 19, and consequent movement of the intermediate portion of the chain 52, independently of the outer portion of the chain; the latter may or may not be held at rest during such time depending upon whether or not the mechanism to be driven by the weight is at rest or in operation, but if it is at rest, the shaft 50 will also be at rest, whereupon the loop 14 will then be shortened and the loop 14^a correspondingly lengthened.

To rotate the sprocket-wheel 19, an electric-motor is employed, which is connected 110 with said sprocket-wheel by a train of gearing. As here shown the sprocket-wheel is secured to a shaft 20, having its bearing in a portion 21 of the frame and having secured to it a ratchet-wheel 38, which engages a pawl 39, borne by a toothed gear 37, which is loosely mounted on the shaft 20, and which engages a pinion 36, secured to a shaft 35, bearing a toothed gear 34, which engages a pinion 33, secured to a shaft 31, bearing 120 a toothed gear 30, which engages a pinion 29, secured to a shaft 28 of an electric-motor 11, illustrated conventionally only, and is supported by the bracket 12 on the frame.

The circuit of the electric-motor is normally open, but is adapted to be closed by a circuit-controller which is operated by or when the weight falls to a predetermined elevation for the purpose of causing the motor to operate and is opened by or when the 125

weight rises to a predetermined elevation for the purpose of causing the motor to cease operating.

The circuit-controller here shown is of the snap switch type and adapted to be operated to close the circuit by pressure upon its plunger, and to open the circuit by a spring, when pressure upon its plunger is relieved.

The particular structure here shown is not, however, of my invention, and is in common use in electric circuits. Generally speaking, it comprises a pair of contact-members 42, a pivoted member 42^a, arranged for engagement therewith, and controlled by a spring 42^b, a sliding member 42^c having a slot, a pivoted member 42^d having a pin arranged to work in said slot and controlling the spring 42^b, and a plunger 48 pivotally connected with said member 42^d, all arranged in a housing 40 and supported by a block of insulation 47 secured to a metal-face plate 49, the plunger 48 projecting through a hole in said plate. When pressure is applied to the plunger 48 to press it inward, the tension of the spring is increased in one direction, and the contact-member 42^a is moved quickly out of engagement with the contact-members 42, and when pressure upon said plunger is relieved, said contact-member 42^a is moved quickly in the opposite direction. I have provided actuating-means for this circuit-controller, one member of which consists of an arm 44, pivoted at 54, and having its upper end-portion with or without a roll thereon, extended over the outer end of the plunger of this switch, for engagement therewith, and said arm has a projection 55, with or without a roll thereon, arranged for engagement with the adjustable traveling-members 45 and 56, to be hereinafter described. Movement of the arm is controlled by these controlling-members 45 and 56, which members consist of cylindrical blocks arranged on a worm 46 and held thereon against rotation by a pin 57 engaging slots therein, but by temporarily removing the pin, either may be revolved on the shaft for relative adjustment thereon, and the block 45 has a recess in its side toward the member 56, so that said member 56 may pass within said recess to give latitude for their relative adjustment, and when adjusted, the pin is replaced in the slots to thereafter hold them as relatively adjusted.

These cylindrical blocks are here shown as having different diameters, to enable arm 44 which engages them to assume and be held in different positions. When engaging the first or largest diameter block 45, the arm will then hold the plunger inward to cause opening of the circuit-controller, so that the circuit to the motor is then open. When the traveling-members are moved along in one direction, by rotation of the

worm, the large diameter member 45 passes from beneath the roll on the projection 55, and said arm is moved by spring pressure in a direction so that its roll will rest upon the smaller diameter member 56, and be held thereby from further operation until said portion is further moved, so that its larger portion also passes from beneath said roll, and more or less revolutions of the worm 46 will be required from the beginning of its operation in the direction above referred to, until the larger portion of the member 56 can pass from beneath said roll, depending upon how it is adjusted. When this larger portion of the member 56 passes from beneath the roll, the plunger will then be allowed to come farther forward and the spring of its circuit-controller then operates to close the contact-members, and thereby close the circuit of the motor. The worm 46 which moves the traveling-members along has secured to it a sprocket-wheel 60, which is engaged by the flexible connection 62, between the two loops 14 and 14^a of the chain 52. As these loops are respectively lengthened and shortened, said flexible connection 62 is correspondingly moved and the sprocket-wheel 60 rotated to in turn correspondingly rotate the worm. As the weight falls, the connection 62 is moved in the direction so that the traveling-members will be moved along on the worm as above described until the circuit-controller is closed. The operation of the electric-motor will then operate the winding-means, and the chain be moved thereby to shorten the loop 14, and to lengthen the loop 14^a. The flexible connection 62 is also moved in the opposite direction to that above referred to and the sprocket-wheel and worm correspondingly reversely rotated and the traveling-members caused to return. As the traveling-members return to their initial positions, the member 56 first passes beneath and thrusts aside the lever 44 and thereby partially depresses the plunger 48, but not enough to cause opening of the switch contacts, said contacts will, therefore, stay closed until the large diameter traveling-member 45 passes beneath the roll on lever 44 which further moves said lever to depress the plunger until the switch contacts will be caused to open and disconnect the current from the motor to thereby stop its further winding.

This motor switch is preferably of the snap variety which moves quickly when opened to prevent maintenance of an arc destructive to the contacts, and its operations are, therefore, directly caused by a spring. If, for any reason, this spring or switch should fail at this critical time to open the circuit, then the motor could continue to wind until something gave way, or damage done to disable the co-operating parts of the motor.

As a safeguard to prevent such danger, I have provided as part of the combination a second normally-closed switch, which is connected in series with the snap switch first mentioned, and this normally-closed switch has an extension directly in the path of motion of the weight to be engaged through an insulator thereon and directly and positively moved thereby to open its contacts and thus insure that no current can thereafter pass to the motor while said weight is in such extremely wound position, and the coöperating parts are further so arranged that no further winding of the weight even by hand thereafter can remove the weight out of path of motion of said switch or allow said switch to be closed until the weight has again dropped below its position for operating said switch.

Said switch comprises an insulating base 72 secured upon the frame 10 by a bolt 73, and a switch arm 74 pivoted at 75 to a stationary switch member 76 and adapted for normal engagement with a second switch member 77, and adapted to be manually operated by the insulating handle 78. Switch arm 74 has an extension 79 which is disposed in the path of movement of a part of the weight, and, as here shown, is adapted to be engaged by the insulating sleeve 80 carried on an extension of the axle of the weight pulley 15, if, for any reason, the main motor control switch should not operate and the motor continue to elevate the weight, thus to positively move switch arm 74 to open position and interrupt the motor circuit and prevent further elevation of the weight.

Switch arm 74 is provided with a spring 81 so connected between the switch arm and the stationary switch member 76 that, in the closed position of the switch arm, it exerts insufficient force upon said arm to open the switch, but upon a movement of said arm, due to the engagement therewith by the moving insulating sleeve 80 of the weight, the spring exerts sufficient force, due to the greater advantage in leverage, to cause the quick separation of the switch contacts.

When the weight runs down, and in case the circuit-controller fails to close the circuit of the motor, or the motor fails to respond, or, for some reason, the winding means fails to operate, the weight will, in such case, continue to move and fall below the position to cause closing of the motor switch. When so continuing to move, the connection 62 and associated parts and the traveling-members will be moved further along on the worm, and as the small diameter part of member 56 passes thus further from beneath the roll, it permits further lateral movement of the member 44, actuated by a spring 58. This member 44 has arranged thereon a stud 44a of insulating material, which, in such case, 65 will then engage one member of a pair of

contact-members 53 and will act to close said contacts. These contact-members 53 are mounted on a block 53a of insulating material, secured to the frame, and are included in an alarm circuit 70, and when closed, will close said circuit, and cause a bell 71, or other means connected in said circuit, to respond. Thus it will be observed that, in case the winding mechanism fails to operate when the weight has fallen to a predetermined elevation, an alarm will be sounded thereby to call attention to such fact. In order to prevent the flexible chain member 62 from ever becoming disengaged from the sprocket 60, I have provided a guard 61, so arranged as to hold said chain in engagement without regard to how slack it may become or be at any time that it may always positively and properly operate said sprocket. The sprocket 18 is loosely mounted on a manually winding-shaft, and has, in addition to the ratchet wheel at one side, which engages a holding pawl on the frame, another ratchet wheel on the opposite side, which is engaged by a winding pawl on a disk mounted on and fastened to the said manually winding shaft, so that the weight may be manually wound in case of any emergency as when the motor or current thereto fails.

I claim:

1. In an automatic winding-mechanism, the combination with a shaft to be driven, of a weight, an endless chain operably connecting said weight with said shaft, said chain having two loop-portions, in one of which the weight is arranged, winding-means connected with said chain between the two loop-portions, which, when at rest, holds the chain at the adjacent sides of the loops and permits movement of those portions of the chain at the opposite sides of the loops by the falling of the weight, that portion of the chain at opposite sides of the loops being connected with the driven-shaft, and when the winding-means operates, that portion of the chain at the adjacent sides of the loops is moved to lift the weight, and automatic means disposed between the loops arranged to cause operation of said winding-means.

2. In an automatic winding mechanism, the combination with a shaft to be driven, of a weight, an endless chain operably connecting said weight with said shaft, a sprocket-wheel engaging said chain, an electric-motor, gearing connecting the motor-shaft with said sprocket-wheel, a circuit-controller for the circuit of said motor, and means arranged between two points of the chain and adapted to close said circuit-controller when the weight falls to a predetermined elevation and to open said circuit-controller when the weight rises to a predetermined elevation.

3. In an automatic winding mechanism,

the combination with a shaft to be driven, of a weight, an endless chain connecting said weight with said shaft, said chain having two loop-portions, one of which supports the weight, the loop supporting the weight being adapted to lengthen and the other loop to shorten, as the weight falls, winding-means connected with the chain arranged to shorten the weight-supported loop to lift the weight and to lengthen the other loop when operated, an electric-motor for the winding-means, a circuit-controller for the circuit of the motor, and means connected with the ends of the loops of the chain and movable back and forth to operate said circuit-controller to open and close the circuit.

4. In an automatic winding mechanism, the combination with a shaft to be driven, of a weight, an endless chain connecting said weight with said shaft, said chain having two loop-portions, one of which supports the weight, the loop supporting the weight being adapted to lengthen and the other loop to shorten, as the weight falls, winding-means connected with the chain arranged to shorten the weight-supported loop to lift the weight, and to lengthen the other loop, when operated, an electric-motor for the winding-means, a circuit-controller for the circuit of the motor, reciprocating actuating-means for said circuit-controller including a chain connecting the ends of the aforesaid loops.

5. In an automatic winding mechanism, the combination with a shaft to be driven, of a weight, an endless chain connecting said weight with said shaft, said chain having two loop-portions, one of which supports the weight, the loop supporting the weight being adapted to lengthen and the other loop to shorten, as the weight falls, winding-means connected with the chain arranged to shorten the weight-supported loop, to lift the weight, and to lengthen the other loop, when operated, an electric-motor for the winding-means, a circuit-controller for the circuit of the motor, reciprocating actuating-means for said circuit-controller including a pivoted actuating-member, a traveling-member controlling said actuating-member, a rotating-member for said traveling member, by which it is moved, and a chain connecting the ends of the aforesaid loops.

6. In an automatic winding mechanism, the combination with a shaft to be driven, of a weight, an endless chain connecting said weight with said shaft, winding-means for the chain, an electric-motor for said winding-means, a circuit-controller for the circuit of said motor, and reciprocating actuating-means for said circuit-controller operated by a movement of said chain.

7. In an automatic winding mechanism, the combination with a shaft to be driven, of a weight, an endless chain connecting said weight with said shaft, winding-means for

the chain, an electric-motor for said winding-means, a circuit-controller for the circuit of said motor, an actuating-member for said circuit-controller, a traveling-member controlling said actuating-member, and means to move said traveling-member, which is associated with the chain.

8. In an automatic winding mechanism, the combination with a shaft to be driven, of a weight, an endless chain connecting said weight with said shaft, winding-means for the chain, an electric-motor for said winding-means, a circuit-controller for the circuit of said motor, an actuating-member for said circuit-controller, a traveling-member controlling said actuating-member, a rotating-member for said traveling-member, and means to rotate said member which is connected with the chain.

9. In an automatic winding mechanism, the combination with a shaft to be driven, of a weight, an endless chain connecting said weight with said shaft, winding-means for the chain, an electric-motor for said winding-means, a circuit-controller for the circuit of said motor, an actuating-member for said circuit-controller, a stepped traveling-member controlling said actuating-member, and means to move said traveling-member which is connected with a chain.

10. In an automatic winding mechanism, the combination with a shaft to be driven, of a weight, an endless chain connecting said weight with said shaft, winding-means for the chain, an electric-motor for said winding-means, a circuit-controller for the circuit of said motor, an actuating-member for said circuit-controller, a stepped traveling-member engaged by said actuating-member, it having two successive steps, thereby to hold the actuating-member in two different positions, and means to move said traveling-member which is connected with the chain.

11. An automatic winding mechanism including a weight, a chain from which the weight is suspended, and means connected between two points of said chain and operated by a predetermined relative movement therebetween to cause the operation of the winding means.

12. An automatic winding mechanism including a weight, an endless chain from which the weight is suspended, said chain having two loop-portions, and means connected between said loop portions and operated by a predetermined relative movement therebetween to cause the operation of the winding means.

13. In an automatic winding mechanism, the combination with a shaft to be driven, of a weight, an endless chain connecting said weight with said shaft, winding-means for the chain, an electric-motor for said winding-means, a circuit-controller for the cir-

cuit of said motor, an alarm-circuit, a circuit-controller for said alarm circuit, and means operated by the chain adapted to control the operation of both circuit-controllers.

14. In an automatic winding mechanism, the combination with a shaft to be driven, of a weight, an endless chain connecting said weight with said shaft, winding-means for the chain, an electric-motor for said winding-means, a circuit-controller for the circuit of said motor, an alarm circuit, a circuit-controller for said alarm circuit, an actuating-member for both said circuit-controllers, a traveling-member for said actuating-member, and means connected with the chain to move said traveling-member.

15. In an automatic winding mechanism, the combination with a shaft to be driven, of a weight, an endless chain connecting said weight with said shaft, winding-means for the chain, an electric-motor for said winding-means, a circuit-controller for the circuit of said motor, an alarm-circuit, a circuit-controller for said alarm circuit, an actuating-member for both said circuit-controllers, a traveling-member controlling

said actuating-member, a rotating-member for said traveling-member and means to rotate said member, which is connected with the chain.

16. In an automatic winding mechanism, the combination with a shaft to be driven, of a weight, an endless chain connecting said weight with said shaft, winding-means for the chain, an electric-motor for said winding-means, a circuit-controller for the circuit of said motor, an alarm-circuit, a circuit-controller for said alarm circuit, an actuating-member for both said circuit-controllers, a traveling-member controlling said actuating-member, consisting of a stepped block having arranged thereon two steps, a rotating-member for said traveling-member and means to rotate said member which is connected with the chain.

In testimony whereof, I have signed my name to this specification, in the presence of two subscribing witnesses.

GEORGE E. KING.
